GEORGE F. HALL, OF NEWARK, NEW JERSEY, ASSIGNOR, BY MESNE ASSIGNMENTS, TO
EASTWOOD-PARK COMPANY, A CORPORATION OF NEW JERSEY.

CIGAR-CUTTER.

1,199,784.

Specification of Letters Patent.

Patented Oct. 3, 1916.

Application filed August 26, 1914. Serial No. 858,589.

To all whom it may concern:

Be it known that I, GEORGE F. HALL, a citizen of the United States, residing at Newark, in the county of Essex and State 5 of New Jersey, have invented certain new and useful Improvements in Cigar-Cutters, of which the following is a specification.

The objects of this invention are to provide an improved cigar cutter having a rotary blade; to provide such a device which will cut the end of a cigar without unduly pressing the same so as to crack it; to provide a blade only a portion of which cuts the cigar; to provide means for using other 10 portions of the blade; to provide improved means for opening and closing the cutter; to secure simplicity of construction and operation, and to obtain other advantages and results as may be brought out in the following 15 description.

Referring to the accompanying drawings in which like numerals of reference indicate the same parts throughout the several views, Figure 1 is an elevation of a cigar cutter embodying my invention looking at the side carrying the rotary blade; Fig. 2 is a similar view showing the device in position after a cut has been made; Fig. 3 is a sectional view on line A—A of Fig. 1; Fig. 4 is an elevation similar to Fig. 1 looking at the device from the opposite direction, and Fig. 5 is a view similar to Fig. 4 showing a modified construction.

In the specific embodiment of the invention illustrated more particularly in Figs. 1 to 4 of said drawings, 1, 2 indicate plates or members slideable with respect to each other. One of these members, as 1, provides at its 20 opposite edges flanges 3, 3 between which the other member 2 may be guided so as to slide in a given direction, which is preferably longitudinally of the device. The outer ends of these plates or members may be suitably formed to be readily operated by the user, 25 and to this end I have shown finger holes 4, 4 thereat. By this means the user may insert two of his fingers and cause the plates to slide back and forth as desired. On the face of the plate 2 upon the opposite side thereof 30 from the wider plate 1 is a knife or blade 5 here shown to be a disk, although I do not restrict myself to any particular shape. Furthermore this blade is pivotally secured upon the adjacent plate or member 2 so as 35 to be rotatable about its center. Preferably

a rivet 6 is used for this purpose extending through both of said plates and the blade, a slot 7 being formed longitudinally of the plate farthest from the blade whereby the plates are held together but free to slide longitudinally of each other. In the plate farthest from the blade is inserted a screw 8 projecting through the other plate 2 and the blade 5, with its head overlying the blade at a distance from the center thereof, said screw being held securely upon the plate 1 by a lock-nut 9. The member 2 adjacent the blade is slotted longitudinally where the screw 8 passes therethrough as at 19, so as to allow the plates to slide longitudinally. 60 Also where the screw passes through the blade, the blade is slotted radially as at 10.

The plate 1 farthest from the blade 5 provides preferably a plurality of holes 11, 12 of different size adapted to receive the end 65 of a cigar or the like which is to be cut, thus giving the user a choice according to the amount which he desires to cut or the size of the cigar or the like to be cut. The margins of these holes are bent outwardly as at 13 70 toward the plane of the knife blade, and terminate in said plane so that the passage of the knife across the same will shear anything inserted through the hole.

In operation, it will be seen that as the 75 plates are slid back and forth, the rivet 6 upon which the knife blade is pivoted has a relative movement in one direction and the screw 8 near the periphery of the blade has a relative movement in the other direction, 80 so that the blade is given a partial rotation. At the same time that the blade is rotated, the plates are slid together as in Fig. 2 so that the blade covers up the holes 11, 12 and at the same time is given a slicing movement 85 by virtue of the rotation thereof. As only a portion of the blade is used to effect this cut I preferably slot the blade radially at other points as 14, 14, similar to the slot 10 so that the screw may be removed from the slot 90 10, the blade turned around and the screw reinserted this time in one of the slots 14. In this manner another portion of the blade 95 is used for shearing the cigars and the like, and when this portion of the blade becomes 100 dull the blade may be again changed.

It will be seen that the construction as described provides that the plates be drawn apart in order to allow the end of the cigar 105 to be inserted in one of the holes 11, 12, and 110

if desired means may be provided for resiliently maintaining said plates in this drawn-apart position, and with this end in view I have shown in Fig. 5 a leaf spring 15 secured upon the screw 8 and bearing against the rivet 6, although other means may be employed for returning the plates to their outward positions, without departing from the spirit and scope of the invention. Furthermore when such means is used, the finger holes 4, 4 may be omitted since it is not necessary for the user to draw the two plates apart, and the outer ends 16, 16 of the plates may therefore form sufficient finger pieces for the user to press the plates slidably together.

It will be noted that the other member, 2 in the drawings, is cut away as at 17 to expose the apertures 11, 12 to the blade 5, said cutting away being upon any suitable line to effect such purpose and yet not interfere with the sliding of the members in alignment. The inner adjacent ends of the finger apertures 4 are furthermore preferably bent over to form rounded flanges 18, said flanges serving to make it easier for the fingers to press the members together. Preferably the range of movement of the two members with respect to each other is limited by the slots 7, 19, or either of them, but if desired movement of the members toward each other in closing the cutter could be limited by engagement of the line 17 of cutting away the member 2 with the bosses or outwardly bent margins 14 of the holes 11, 12, or by engagement of the ends of the two members away from their finger holes with the flanges 18, 18 at the inner edges of said finger holes. Furthermore, instead of the removable screw 8, a rivet similar to the rivet 6 could be employed and the additional slots 14, 14 dispensed with, for cheapness. Any suitable and well-known equivalents of either rivets or screws could of course be used, and I have employed in the claims the generic term "tie means" to cover anything of the sort.

Obviously various detail modifications may be made in manufacturing my improved cigar cutter without departing from the spirit and scope of the invention, and I do not wish to be understood as limiting myself except as required by the following claims when construed in the light of the prior art.

Having thus described the invention, what I claim is.

1. In a cigar cutter, opposite plates arranged to slide longitudinally of each other, a rotary knife, and means extending through all three of said parts holding the same flatwise together and at the same time permitting a limited sliding movement of the plates and rotary movement of the knife.

65 2. In a cigar cutter, opposite plates ar-

ranged to slide longitudinally of each other, a rotary knife, and a rivet or the like extending through all three of said parts holding the same flatwise together and at the same time permitting a limited sliding movement of the plates and rotary movement of the knife.

3. In a cigar cutter, opposite plates arranged to slide longitudinally of each other, a rotary knife, and a plurality of means extending through all three of said parts one of said means being nearer one side edge of the plates than the other side edge and eccentric with respect to the knife and another of said means being substantially midway between said side edges of the plates and concentric with the knife, both said means holding the said plates and knife flatwise together and at the same time permitting a limited sliding movement of the plates and a limited rotary movement of the knife.

4. In a cigar cutter, opposite plates arranged to slide longitudinally of each other, a rotary knife, and means extending through all three of said parts substantially midway between the side edges of the plates and concentric with respect to the knife, said means holding the said plates and knife flatwise together and at the same time permitting a limited sliding movement of the plates and rotary movement of the knife.

5. In a cigar cutter, opposite plates arranged to slide longitudinally of each other, a rotary knife, and means extending through all three of said parts nearer one side edge of the plates than the other and eccentric with respect to the knife, said means holding the said plates and knife flatwise together and at the same time permitting a limited sliding movement of the plates and a limited rotary movement of the knife.

6. In a cigar cutter, opposite plates arranged to slide longitudinally of each other, a rotary knife, means extending permanently through all three of said parts substantially concentric with respect to the knife for holding said parts permanently together flatwise of each other and at the same time permitting a limited sliding movement of the plates and rotary movement of the knife, and removable means eccentric with respect to the knife adapted to rotate the knife as the plates are slid, and adapted to be removed and positioned at a different part of the knife for changing the effective cutting edge of the knife.

7. In a cigar cutter, opposite plates arranged to slide longitudinally of each other, a rotary knife, and means extending through all three of said parts substantially concentric with respect to the knife for holding said parts flatwise together, one of said plates having a slot through which said means extends thereby permitting the plates

to slide, the ends of the slot forming stops against which said means will engage to limit movement of the plates.

8. In a cigar cutter, opposite plates arranged to slide longitudinally of each other, a rotary knife, means extending through all three of said parts substantially concentric with respect to the knife for holding said parts flatwise together, one of said plates having a slot through which said means extends thereby permitting the plates to slide, the ends of the slot forming stops against which said means will engage to limit movement of the plates, and means for rotating said knife as the plates are slid.

9. In a cigar cutter, opposite plates arranged to slide longitudinally of each other, a rotary knife, and means extending through all three of said parts eccentric with respect to the knife for holding said parts flatwise together, one of said plates having a slot through which said means extends thereby permitting the plates to slide, the ends of the slot forming stops against which said means will engage to limit movement of the plates.

10. In a cigar cutter, opposite plates arranged to slide longitudinally of each other, a rotary knife, and means fast with respect to one plate, the other plate having a slot through which said means extends so as to permit the plates to slide, said means also holding said plates and knife flatwise together.

11. In a cigar cutter, a plate, a knife, means connecting said plate and knife, and another plate between the first mentioned plate and knife and slidable with respect thereto, the middle plate being adapted to engage said connecting means and be limited in movement thereby.

12. In a cigar cutter, opposite plates arranged to slide longitudinally of each other, a rotary knife, and tie means extending through all three of said parts, one of said means being concentric with respect to said knife and the other being eccentric and both said means serving as stops to limit movement of the plates with respect to each other.

13. In a cigar cutter, opposite plates arranged to slide longitudinally, a knife, and a pair of tie means extending each through

both of said plates and knife, one of said tie means being fixed with respect to one plate and the other tie means being fixed with respect to the other plate and each means adapted to engage the other plate for limiting movement thereof.

14. In a cigar cutter, opposite plates arranged to slide longitudinally, each of said plates having a slot therein, a knife, and a pair of tie means extending each through one of the slots and fixed with respect to the other plate and extending through the knife, the plates being thereby adapted to slide and said means adapted to engage the ends of the slots as stops.

15. In a cigar cutter, a knife, a pair of plates arranged to slide longitudinally with one plate between the other and the knife, the plate farthest from the knife having a cigar opening therein, means for passing the knife across the cigar opening as the plates are slid together, and a raised margin around the cigar opening to the plane of the cutting edge of the knife whereby space is afforded for the plate between the other plate and the knife and at the same time a close contact between the knife edge and the margin of the cigar opening may be obtained.

16. In a cigar cutter, a knife, a plate having the knife pivotally carried adjacent its end, said plate having also an extension along one side beyond the pivotal support of the knife, and a second plate slidable flatwise of the first-mentioned plate upon the side thereof away from the knife, said second mentioned plate having flanges at its side edges providing a bearing for the first mentioned plate and its extension.

17. In a cigar cutter, opposite plates arranged to slide longitudinally of each other, a rotary knife arranged and adapted to slide and rotate as the plates are slid, and lateral or rounded flanges at opposite end portions of the plates transverse to the planes thereof whereby the plates may be held between the operator's fingers and slid together.
